UNITED STATES PATENT OFFICE.

JOHN SAMUEL HUNTER, OF COALINGA, CALIFORNIA.

PUMP.

Application filed March 1, 1926. Serial No. 91,548.

This invention aims to provide a novel means whereby a pump barrel may be lowered into a casing in a well, and be withdrawn therefrom, without difficulty.

5 It is within the province of the disclosure to improve generally and to enhance the utility of devices of that type to which the invention appertains.

With the above and other objects in view 10 which will appear as the description proceeds, the invention resides in the combination and arrangement of parts and in the details of construction hereinafter described and claimed, it being understood that 15 changes in the precise embodiment of the invention herein disclosed, may be made within the scope of what is claimed, without departing from the spirit of the invention.

In the accompanying drawings:—

20 Figure 1 shows in longitudinal section, a device constructed in accordance with the invention, the barrel being held in the casing;

Figure 2 is a longitudinal section wherein 25 the parts are shown as they will appear when the operation of pulling out the barrel is about to be begun;

Figure 3 is a detail enlarged from Figure 1;

30 Figure 4 is a sectional top plan;

Figure 5 is a cross section taken about on the line 5—5 of Figure 1.

The numeral 1 marks a tubular casing. The casing 1 has an enlarged upper end 2. 35 The end 2 of the casing is connected, in any desired way, with the well tubing (not shown). At its lower end, the casing 1 has a tapered bore 3. A barrel 4 is disposed in the casing 1. The barrel 4 has a tapered 40 end 5. The tapered end 5 of the barrel 4 is seated in the tapered bore 3 of the casing 1. Intermediate its ends, the barrel 4 is supplied with internal projections 6. A

holder 7, in the form of a ring, is threaded 45 or secured otherwise in the end 2 of the casing 1. Longitudinal, transversely spaced, resilient keepers 8 are provided. The upper ends of the keepers 8 are secured to the ring 7. The lower ends of the keepers 8 extend

50 below the ring 7 and are free. The lower ends of the keepers 8 have shoulders or the like, shown at 9. The keepers 8 tend to spring inwardly, so as to cause the shoulders 9 to engage the upper end of the barrel 4 and to hold the barrel down. The hold of 55 the shoulders 9 on the upper end of the bar-

rel 4 is enhanced, because the keepers 8 are supplied, intermediate their ends with outwardly extended resilient arms 10 which bear on the ring 7 and aid in swinging or springing the lower ends of the keepers 8 inwardly. On the inner surfaces of the lower ends of the keepers 8 there are inwardly extended rounded lugs 11. A plunger 12 reciprocates in the barrel 4. The plunger 12 is a composite structure. It includes a piston 14, a cage 15 mounted on the piston, a downwardly closing ball valve 16 in the cage, and a coupling 17 connected to the cage. An operating member 18, such as a rod, is assembled 60 at its lower end with the coupling 17. The rod 18 carries a releaser 19, which may be a block.

A cage 20 is shown, and the body 21 of the cage is threaded at 22 into the lower end of the barrel 4, to engage the tapered extremity 23 of the body 21, in the tapered end 5 of the barrel 4. A downwardly closing foot valve 24 operates within the cage 20.

When it is desired to withdraw the barrel 4 from the casing 1, the plunger 12 is pulled upwardly by the rod 18 until the releaser 19 engages the lugs 11 on the keepers 8 and swings the keepers outwardly, out of engagement with the upper end of the barrel 4, as shown in Figure 2. Some part of the plunger 12, generally the base of the cage 15, comes into contact with the projections 6 on the barrel 4, and, thus, the barrel may be pulled out of the casing 1 readily, along 80 with the rod 18. By a reverse operation, which will be understood readily when Figure 2 is examined, the barrel 4 may be lowered into the casing, and when the releaser 19 moves downwardly out of engagement 85 with the lugs 11, the keepers 8 will engage with the upper end of the barrel 4, as depicted in Figure 1.

When the rod 18 makes an ordinary stroke to consummate the pumping operation, the releaser 19 does not come into contact with the lugs 11 on the keepers 8, nor does the plunger 12 come into contact with the projections 6.

What is claimed is:—

A device of the class described, comprising a barrel and a casing wherein the barrel is seated against downward movement, a ring, means for detachably mounting the ring in the casing, in accessible relation to one end of the casing, a spring keeper secured at its upper end rigidly to the ring,

the lower end of the keeper being provided with a recess that receives the end of the barrel, an inwardly extended lug on the lower end of the keeper and disposed above the recess, a pumping plunger slideable in the barrel, an operating member carrying the plunger, the barrel being provided with a projection which the plunger engages to raise the barrel when the operating member

is raised beyond the limit of a pumping stroke, and a releaser on the operating member and engaging the lug on the keeper to flex the keeper and disengage the recess from the upper end of the barrel when the operating member is raised sufficiently.

In testimony that I claim the foregoing as my own, I have hereto affixed my signature.

JOHN SAMUEL HUNTER.
